Primary Examiner — Cynthia Ramirez(74) *Attorney, Agent, or Firm* — Allen, Dyer, Doppelt +
Gilchrist, PA(57) **CLAIM**

The ornamental design for a part for a pallet, as shown and described.

DESCRIPTION

FIG. 1 is a perspective view of a part for a pallet showing our new design;

FIG. 2 is a left-side view thereof;

FIG. 3 is an enlarged end view thereof;

FIG. 4 is a right-side view thereof;

FIG. 5 is an enlarged view of the other end thereof;

FIG. 6 is a bottom view thereof; and,

FIG. 7 is a top view thereof.

The broken lines shown in the figures are included for the purpose of illustrating portions of the part for a pallet which forms no part of the claimed design.
